UNITED STATES PATENT OFFICE.

GEBHARD C. BOHN, OF ST. PAUL, MINNESOTA.

REFRIGERATOR-CLOSURE.

1,329,453.

Specification of Letters Patent.

Patented Feb. 3, 1920.

Application filed April 5, 1917. Serial No. 160,067.

To all whom it may concern:

Be it known that I, GEBHARD C. BOHN, a citizen of the United States, residing at St. Paul, in the county of Ramsey and State of Minnesota, have invented certain new and useful Improvements in Refrigerator-Closures, of which the following is a specification.

My invention relates to improvements in refrigerators and analogous constructions, particularly of that type which have an outer sheathing or casing of enameled sheet metal.

One object of my invention is to provide a construction of the character designated, in which the outer sheathing is retained in position without the necessity of exterior fastening devices marring the exterior appearance of the refrigerator and without the necessity of drilling holes in the sheathing.

Another object of my invention is to provide a construction in which the enameling upon the sheathing is protected against chipping or other injury as in the closing of the refrigerator door.

My invention further consists in improved means for securing the enameled inner lining in position.

30 In the accompanying drawings forming part of this specification.

Figure 1 is a perspective view of a portion of the front wall of a refrigerator showing the door and surrounding frame work with a portion of each partly broken away, and

Fig. 2 is a horizontal section through a portion of the door and adjacent refrigerator wall.

40 Referring to the drawings, A represents a refrigerator body and 2 enameled plates forming an exterior covering or sheathing for said body. 3 represents enameled lining plates for the interior of the refrigerator, the door B of the refrigerator being likewise exteriorly covered by enameled sheathing plates 4 and covered upon its inner side with enameled lining plate 5.

50 In order to secure the sheathing and lining plates for the body portion of the refrigerator in position I provide the molding strips 6 secured around the inner face of the door opening. As shown in Fig. 2 the outer covering or sheathing is bent over the outer edge of the door opening and the lin-

ing is bent outwardly over the inner edge of the door opening so as to be overlapped by the molding 6, which molding is suitably secured inside the door opening. The exterior sheathing for the door is carried inwardly around the edge of the door, as shown in Fig. 2, to form a grip over the door edge. The lining for the door is bent outwardly over the edge of the door and held in position by the molding 7 which overlaps the lining and is suitably secured to the door edge. The molding 6, secured to the body of the refrigerator, is cut away to form a shoulder or stop 8 against which the molding 7 carried by the door contacts in closing, the outer flange 9 of the door striking against the body of the molding 6.

In order to avoid chipping or injury to the enameled sheathing plates of the door and body of the refrigerator I form the sheathing along the door opening with an outwardly bent rib 10, the inner side of the door flange 9 being formed with a groove 11 to receive said rib. The sheathing for the door terminates short of the groove 11 so that in the closed position of the door the rib 10 contacts with the wood portion of the door in which the groove 11 is formed. As shown in Fig. 2 the parts may be so fitted as to hold the sheathing of the door 85 slightly separated from the sheathing of the body of the refrigerator, thus further obviating the danger of injury to the enameled plates. In order to prevent binding of the door and casing, as by swelling, the moldings 6 and 7 are preferably proportioned to leave a slight space 12 when the door is closed, and the outer door flange cut away to leave a slight space 13.

Through the medium of the features of construction and combination described, I am able to entirely cover the refrigerator box and door with enameled plates without the necessity of the exterior fastening devices ordinarily employed and without the necessity of any fastening means passing through the plates themselves. By means of the described combination of parts which allow the enameled plates to stand in contact with yielding material, as the wood-work of the door, when the door is closed, chipping of the enameled plates by the slamming of the door is prevented. In the use of the word "enamel" in the foregoing specification I employ the same as describ- 110

ing any sheathing or lining which is subject to chipping or cracking and do not restrict myself to the vitreous enamel porcelain.

I claim:

5. In combination with a refrigerator body formed with a door opening, a door hinged therein, an enameled sheathing for said refrigerator body extending around the edge of the door opening, an enameled sheathing for said door extending around the edge of the door, and non-metallic fastening means for the sheathing of said body secured within the door opening and serving as a cushioning means for the door.
10. In combination with a refrigerator body formed with a door opening, and a door fitted in said opening, an enameled sheathing or covering for said body, said sheathing being carried around the edge of the door opening, and a non-metallic molding secured to the inner face of the door opening and overlapping said sheathing to secure it in position and also constitute a stop for the door to seat against.
15. In combination with a refrigerator body formed with a door opening and a door fitted thereto, an enameled outer covering or sheathing for said body portion bent over the outer edge of the door opening, an enameled lining for said body bent outwardly over the edge of the inner edge of the door opening and a non-metallic molding secured to the inner face of the door opening between the bent over edges of the lining and outer sheathing to form a stop for the door and overlapping both said lining and sheathing.
20. A refrigerator comprising a body portion formed with a door opening, a door fitted to said opening, enameled sheathing plates forming an exterior covering for said body portion and bent outwardly around the door opening to form a rib and enameled sheathing plates covering said door and bent around the edge thereof, said door being
25. formed of non-metallic material and provided with a groove adjacent to the free edge of the door covering plate to receive said rib.

5. A refrigerator comprising a body portion formed with a door opening, and a door fitted thereto, enameled sheathing and lining plates covering said body portion and bent over the edges of the door opening, fastening means secured inside the door opening and overlapping said plates, enameled sheet metal sheathing and lining plates for said door, said plates overlapping the door edge, and a non-metallic seat forming part of said door and contacting with the exterior sheathing of said refrigerator when said door is closed.

6. A refrigerator comprising a body formed with a door opening, a door for closing the latter having a non-metallic flange overlapping the body about the door opening, an enameled sheathing plate forming an exterior covering for said body and bent outwardly beneath the door flange to form a rib about the door for spacing the non-metallic door flange from the sheathing plate, an enameled sheathing plate covering the door and bent around the edge of the flange thereof but terminating short of the point of contact of the rib with said flange, sheathing plates forming interior coverings for the body and door, non-enameled means securing the interior sheathing plate of the door to the door, and like means for securing the sheathing plates of the body in position and forming a seat for the first means.

7. A refrigerator comprising a body formed with a door opening, a door for closing the latter, enameled sheathing and lining plates for the exterior and interior surfaces of the body and the door, and non-metallic means for securing the body plates in position and serving as a cushioning means for the door during closing movement to prevent one enameled plate from striking against another.

In testimony whereof I affix my signature in presence of two witnesses.

GEBHARD C. BOHN.
